UNITED STATES PATENT OFFICE.

JAMES M. HOPKINS, OF CHICAGO, ILLINOIS, ASSIGNOR TO Q. & H. COMPANY, OF CHICAGO, ILLINOIS, A CORPORATION.

MEANS FOR SUPPORTING DOOR-HANGER TRACKS.

No. 889,012.

Specification of Letters Patent. Patented May 26, 1908.

Application filed March 6, 1908. Serial No. 419,422.

To all whom it may concern:

Be it known that I, JAMES M. HOPKINS, a citizen of the United States, and a resident of Chicago, in the county of Cook and State of Illinois, have invented certain new and useful Improvements in Means for Supporting Door-Hanger Tracks, of which I do declare the following to be a full, clear, and exact description, reference being had to the accompanying drawing, forming part of this specification.

The present invention has for its object to provide improved means for movably supporting the doors of railway cars, and the invention consists in the features of novelty hereinafter described, illustrated in the accompanying drawing and particularly defined in the claims at the end of this specification.

Figure 1 is a view in vertical section through a portion of a railway freight car embodying my invention. Fig. 2 is a view similar to Fig. 1, but showing a slightly modified form of the invention. Fig. 3 is a view similar to Fig. 1, but showing a further modified embodiment of the invention. Fig. 4 is a front view upon a reduced scale of the upper portion of a car having my invention applied thereto.

As shown, my invention is embodied in what is known as an "all metal" car, but it will be manifest that it is applicable also to railway cars of the ordinary type.

7 designates the rail (preferably a channel bar) extending from end to end of the car beneath the eaves of the roof 8. Below the rail 7 is formed the usual doorway, in front of which will slide the door 9 which, as shown, is formed of plate metal. To the upper portion of the door 9 are secured, as at 10, the hangers 11. As shown in Fig. 1, each of the hangers 11 is provided at its upper end with a hood 12 within which is journaled a bearing roller 13, this bearing roller being mounted upon a spindle 14 that projects inwardly from the hood 12. Each of the bearing rollers 13 rests upon a track 15 formed of metal and, as shown in Fig. 1, this track has a depending flange 16 inside of which extends the upwardly projecting lug 18 that is formed upon the hanger 11. This lug 18 serves to guard against the accidental passage of the roller 13 from the track 15.

The track 15 will extend above the doorway of the car and integral with this track

15 is formed a part 20 that affords means whereby the track will be secured to the body of the car. Preferably, and as shown in the several views of the drawing, the top of the suspension part 20 of the track has formed 60 integral therewith inwardly and downwardly bent flanges 21 and 22 that interlock with the plate 7 of the car body.

By providing the track 15 with integral means whereby it may be connected with 65 and sustained from the body of the car, the necessity of employing separate brackets for supporting the track 15 is avoided; and as these several parts are rolled from a single plate of metal, they can be very cheaply and 70 conveniently made and will afford a strong and durable construction. Moreover, by forming the part 20 at its top with means whereby it may interlock with or hook on to a part of the car body, a simple and efficient 75 means is provided whereby the track can be quickly placed in position and can be securely and rigidly retained.

In the form of the invention illustrated in Fig. 2, the plate 7 of the car body has interlocked therewith the flanges 21 and 22 of the track suspension part 20, but in this embodiment of the invention the track 15^a is formed, by an upwardly bent flange integral with the part 20. Upon this track 15^a will rest each 80 of the grooved bearing rollers 13^a that sustain the car-door 9. Each of the rollers 13^a is journaled at the upper end of a hanger 11^a that is secured, as at 10, to the car door 9.

In the form of the invention shown in Fig. 90 3, the plate 7^a that extends above the doorway of the car consists of a flat metal plate with the upper edge of which interlock the flanges 21^a and 22^a of the track suspension member 20. In this form of the invention 95 the track 15^b is formed integral with the bottom of the suspension member 20 and upon this track rests each of the bearing rollers 13^b. Each bearing roller 13^b is journaled at the upper end of the hanger 11^b that is secured as at 10 to the car door 9. In this last 100 described form of the invention a short angle bar 25 is fastened to and projects inwardly from the upper portion of the car door 9, the upper part of this angle bar engaging with the 105 lower portion of the plate 7^a and serving to hold the car door against displacement.

In the several forms of the invention above described, the track has formed integral therewith a suspension member whereby it is 110

connected to the body of the car and integral with the top of this suspension member are also preferably formed flanges adapted to interlock with a portion of the car body; and 5 with any of the several forms of the invention the necessity for employing separate brackets is avoided and a strong, durable and efficient means is provided for connecting the door track with the body of the car.

10 It is manifest that the precise details of construction above set out may be varied without departing from the scope of the invention.

15 Having thus described my invention, what I claim as new, and desire to secure by Letters Patent, is:—

1. The combination with a car body, of a track extending above the doorway and having an integral, upwardly extending part 20 constructed to interlock with a part of the car body.

2. The combination with a car body, of a track extending above the doorway and hav-

ing an integral, upwardly extending suspension member having a hook-shaped part at 25 its top adapted to engage a part of the car body.

3. The combination with a car body, of a suspension member extending above the doorway, said suspension member having 30 formed integral with its lower end an outwardly projecting rail and with its upper part a hook-shaped portion adapted to interlock with a part of the car body.

4. The combination with a car body comprising in its construction a plate extending above the doorway of the car, of a track suspension member extending over the doorway and having formed integral with its lower end a track and with its upper end a flanged portion 40 adapted to interlock with said plate.

JAMES M. HOPKINS.
